UNITED STATES PATENT OFFICE.

ARTHUR J. BENNETT, OF CAMBRIDGE, OHIO.

DESIGN FOR A GLASS ARTICLE.

52,693.

Specification for Design. Patented Nov. 19, 1918.

Application filed December 2, 1916. Serial No. 134,780. Term of patent 7 years.

To all whom it may concern:

Be it known that I, ARTHUR J. BENNETT, a citizen of the United States, residing at Cambridge, in the county of Guernsey and State of Ohio, have invented a new, original, and ornamental Design for Glass Articles, of which the following is a specification, reference being had to the accompanying drawing, forming part thereof.

Figure 1 is a side elevation of a goblet showing my new design;

Fig. 2 is a top plan view the bowl being omitted; and

Copies of this patent may be obtained for five cents each, by addressing the "Commissioner of Patents, Washington, D. C."

Fig. 3 is a section on the line 3—3 of Fig. 1 the base being omitted.

The present invention resides in the stem shown as associated and used with structures of similar nature.

I claim:

The ornamental design for a glass article, as shown.

ARTHUR J. BENNETT.
